TYPEWRITING MACHINE

Original Filed Sept. 5, 1922

Fig. 1.

UNITED STATES PATENT OFFICE.

OTTO THIEME, OF HARTFORD, CONNECTICUT, ASSIGNOR, BY MESNE ASSIGNMENTS, TO UNDERWOOD COMPUTING MACHINE COMPANY, OF NEW YORK, N. Y., A CORPORATION OF NEW YORK.

TYPEWRITING MACHINE.

Original application filed September 5, 1922, Serial No. 586,074. Divided and this application filed October 24, 1924. Serial No. 745,532.

The present invention relates to typewriting machines, and more specifically to column-stop bars and column-stops.

One object of the invention is the provision of means for adjusting, setting and holding the column-stop bar or rack in such position that the stops, when set thereon at indicated column positions, will be accurately set.

Another feature of the invention is a column-stop which may be placed and replaced on the stop-bar with minimum trouble; and which, although of cheap and simple construction, is of great strength and rigidity, in its interlockment with the stop-bar, to withstand the impacts of the carriage in the jumps of the latter from one to another column position.

This application is a division of my co-pending application, Serial No. 586,074, filed September 5, 1922 (now Patent No. 1,517,474, dated December 2, 1924).

Other features and advantages will hereinafter appear.

In the accompanying drawings,

Figure 1 is a top plan view, of the carriage of a typewriting machine, with parts broken away.

Figure 2 is a side elevation, partly in section.

Figure 3 is a front view, partly broken away, showing the adjustable attachment of the stop and scale bar to the carriage.

Figure 4 is a detail view, in top plan, partly broken away, of the mechanism shown in Figure 3.

Figure 5 is a rear view, both right and left hand side, of the mechanism, the right-hand side of which is shown at Figure 3.

Figure 6 is a perspective view of one of the stops.

Referring to the drawings, the platen 10 is carried by an axle 11 journaled in arms 12 forming part of a frame pivoted on a shaft 13, which connects and is carried by side plates 14 of the carriage. The normal or printing position of the platen and of the frame pivoted on the shaft 13 is that shown in Figure 2. These parts may be swung up around the shaft 13, to permit fanfold or manifold webs to be advanced in a well-known manner, for detachment of the leading or written section thereof and for place-

ment of the succeeding section. The line-space movement of the platen, by means of hand-wheels 15 and by means of a line-space lever 16, may be effected, both when the platen is in its normal position and when it has been swung up for a gross movement of the web.

For this purpose, there is a gear 17 attached to each end of the platen-axle 11, each gear 17 being in mesh with one of two gears 18 journaled on the shaft 13, and each gear 18 being in mesh with one of two gears 19 fastened on stub shafts 20 journaled in the side plates of the carriage. Each shaft 20 has fastened thereto one of the hand-wheels 15. The left-hand shaft 20 also has fastened thereto a ratchet-wheel (not shown), forming part of a line-spacing mechanism operable by the line-space lever 16. This line-spacing mechanism is not fully shown in the drawings, but is of the construction found in Underwood typewriting machines.

Line-space movement of the shaft 20, whether by the wheel 15 or by the line-spacing mechanism, causes the gear 19 to turn the gear 18, and, through the latter, to turn the gear 17 and with it the platen. When the platen is swung up around the shaft 13, the gears 17 remain in mesh with the gears 18, and consequently the line-space movement of the platen may be effected, as when the parts are in the printing position.

The swinging frame is shown as having a paper-shelf 21 secured to a cross-bar 22 thereon, and as having side plates or arms 23 provided with pins 24 adapted to be engaged by hooks 25 fast to a rock-shaft 26 journaled in side members 27 of the carriage. A spring 28 causes the hooks 25 to be thrust forward to engage the pins 24 on the swinging frame, thereby locking the latter and the platen down in normal or printing position. In moving the platen to normal position, the pins 24 force back the hooks 25 until the latter are free to swing over the pins. For releasing the hooks to permit the platen to be swung up, the left-hand hook is shown as extended at 29 to carry a finger-piece 30 by means of which the hooks and rock-shaft 26 may be swung backward until the hooks are clear of the pins 24.

The carriage is shown as provided with

the usual paper-guide and apron 31 carried by a cross-piece 32, which connects the side plates of the carriage. The carriage has movement in letter-feed and return directions on a rod 33 on the main frame 34 of the typewriting machine. The parts thus far described are not new with the present invention.

Brackets 43 and 44 move to hold the column-stop bar. This bar is in the form of a rack 58, the teeth of which are on the under side thereof. The upper face 59 of the bar is graduated at letter-space distances, numbered to correspond to the graduations and numbering on the usual letter-space scale 60 on the front cross-piece of the main frame of the machine. For accurate positioning of the rack teeth and scale of the stop-bar to bring the scale 59 into exact accord with the scale 60, in assembling the machine, and occasionally for readjustment, it is desirable that the bar 58 be adjustable lengthwise of the platen. Such adjustment is provided for as follows. The horizontal arms 61 of the brackets 43 and 44 have blocks 62 secured to the upper faces thereof by pins 63. The under side of the stop-bar 58 is cut away, as at 62^a, to receive and bear upon the faces of the blocks 62, with the under face of said bar also bearing upon the face of each arm 61. These blocks are slotted at 64 lengthwise to the bar 58, and are hardened to resist wear at the slots. Below the blocks 62, the horizontal arms 61 of the brackets 43 and 44 have holes 65 therethrough to receive heads 66 of screws 67, which pass through the slots 64 in the blocks 62 and through the bar 58, and which are held in place by nuts 69 on the top of the stop-bar 58. The heads 66 of the screws 67 bear against the under faces of the blocks 62, and when the nuts 69 are tightened the bar is held against movement with the heads enclosed by the arms 61. The holes 65 in the arms 61 of the brackets are of such size that when the nuts 69 are loosened the screws 67 may have movement with the bar lengthwise of the slots 64 in the blocks 62. This movement is effected and controlled by a turn-screw 70, which is threaded into the right-hand end of the stop-bar, and which has a head 71 adapted to bear against a finger or offset 72 on a third arm 73 of the bracket 43. The head of the screw 70 has holes 74 therein to receive a pin for turning the screw. When the head of the screw is bearing upon the offset 72, movement of the screw in one direction will effect a delicately controlled movement of the bar to the left; provided the screws 67 have been loosened. Turning the screw 70 in the other direction, while pressing the bar to the right, results in a delicately controlled movement of the bar in that direction.

By placing one of the column-stops on the

bar 58, throwing the carriage to the same, and reading the position of the carriage from the scale 60 on the main frame of the machine, the accuracy of setting of the bar 58 may be determined. When accurately set, the bar is locked by the screws 67 with the head 71 of the screw 70 against the offset 72 of the bracket 43. If the screws 67 become loosened and the bar 58 accidentally disturbed, readjustment of the same in the manner just indicated may be readily effected.

One of the column-stops is shown in Figure 6. This stop is shown as a block 75 grooved or channeled to present a plurality of teeth 76, three such teeth being shown, and each tooth being adapted to enter and fit between two adjacent teeth of the rack 58. A sheet-metal finger 77 has ears 78, by means of which it is pivoted at 79 to the block 75. A coil spring 80, seated in a pocket in the block 75, bears upward against the rear end of the finger 77 to force down the front end of said finger. The stop is forced onto the stop-bar from the rear of the latter; the teeth 76 of the stop first engaging with the teeth of the rack, and the finger 77 is vibrated against the action of the spring 80 in passing over the top of the stop-bar.

In order that the finger 77 may be vibrated in the operation of placing the stop, the forward end of the finger is inclined upward and forward, as at 81, and preferably the forward ends of the teeth 76 are tapered down, as at 82. The inclined lip 81 at the forward end of the finger 77 forms part of a V-shaped detent 83, which snaps over the forward edge of the stop-bar to hold the stop to the latter after the stop has been thrust into home position. Another detent 84 of the finger 77 serves as a tooth or bearing for the latter on the top of the bar, and as a stop to determine the throw of the finger under the action of the spring 80. In order that the stop may find its position in the rack without trouble to the operator, the upper edges of the inclined portion 82 of the teeth 76 are preferably beveled, as indicated at 85. To prevent overthrow of the finger 77 and possible displacement of the spring 80 when the stop is not in use, there is a tooth 86 formed on one of the ears 78 of the finger 77 for engagement with a pin 87 on one side of the block 75.

For co-operation with the denominational-stops, the block is provided with an elongated tooth or lip 88 which depends from the lower face thereof into the field of action of the denominational-stops. After the tooth 88 has been stepped beyond the denominational-stop, the latter may be lifted up behind the tooth 88, and under the block 75, preliminary to a jump of the car-

riage to the next column-stop. The tooth 88 is beveled at one edge, so that the denominational-stop may not be blocked thereby on being lifted. The denominational- 5 stop mechanism may be that found on the standard Underwood typewriting machine, and so is not here shown or described.

It will be noted that the hardened blocks 62 co-operate with the faces of the arms 61 10 to provide a long surface contact against the under face of the stop-bar to resist displacement of the bar when the two surfaces are clamped together by the screws 67; that the assembly of the blocks 62 on the upper faces 15 of the arms 61 provides that the heads of the screws may be concealed by the arms and not project into the path of the denominational tabulator-stops; and that the shock resisting column-stop-bar-clamping means is 20 reinforced by a jack-screw threaded into one end of the stop-bar with the head thereof abutting a fixed part of one arm 61.

Variations may be resorted to within the scope of the invention, and portions of the 25 improvements may be used without others.

Having thus described my invention, I claim:

1. In a typewriting machine having a slotted column stop-bar, a detachable column- 30 stop including a block of hard material having a plurality of elongated teeth with beveled and pointed tooth ends to promote a 35 slidable entrance of the teeth in the slots of the stop-bar, said block having a depending tooth forming an integral part thereof for co-operating with tabulating plungers to arrest the carriage, and a detent pivoted to the column-stop to engage with the stop-bar after the initial engagement of the teeth 40 on the column-stop with the stop-bar.

2. In a typewriting machine, the combination of a column stop-bar having letter-spaced rack-teeth thereon, a detachable column-stop including a block of hard material, 45 said block having a plurality of elongated teeth slidably engageable through the rack-teeth of the bar and formed with a stop-face to limit the sliding movement of the column-stop across the stop-bar, said 50 block having a depending tooth forming an integral part thereof for arresting the carriage, and a self-opening stop-retaining detent pivoted to the column-stop and engageable with the stop-bar, said detent being pivotally mounted on said block and having 55 means for locating the block on the bar and for preventing accidental displacement of the block.

3. In a typewriting machine, the combination of a column stop-bar having letter-spaced rack-teeth thereon, a detachable column-stop including a block of hard material, 60 said block having formed integrally therewith a plurality of elongated teeth to slidably engage adjoining rack-teeth on the

stop-bar and a depending tooth, forming an integral part of said block, for engaging with tabulating mechanism, and a self-opening stop-retaining detent pivoted to the column-stop and engageable with the stop-bar 70 in a manner to contact with the side of the bar opposite to the side having the teeth.

4. In a typewriting machine including a carriage having rearwardly-extending arms on each end thereof, the combination of a 75 column stop-bar having detachable column-stops thereon to effect the arrest of the carriage at predetermined column positions along the line of printing, means for adjustably securing said column stop-bar and the 80 column-stops to the carriage, including a hard slotted block secured to the face of each carriage-arm to support the stop-bar at each end, a screw passing through the slot from the under side through the stop-bar, and a 85 check-nut for the screw to bear upon the stop-bar, the head of said screw entering a clearance hole in the carriage-arm to bind against the under face of the block with the head concealed by the arm, and a jack- 90 screw threaded into one end of the stop-bar and having a head adjustable to a stop-ear on one carriage-arm to reinforce the screw-clamped position of the stop-bar to resist 95 the impact of the carriage in a column-skipping direction.

5. In a typewriting machine, the combination of a column stop-bar in the form of a toothed rack, a column-stop detachably settable on the bar and including a solid member formed with a plurality of teeth slidably engageable with adjoining teeth on one side of the bar, said member having also a depending tooth formed integral therewith, and a stop-face to limit the sliding engagement thereof, and a detent pivoted to said member and formed with a flat V-shaped terminal the width of the member to cam over and engage the opposite side of the stop-bar, said detent having also means for 100 engaging said opposite side of the bar to thereby force the teeth on the member into engagement with the teeth on the stop-bar. 105

6. In a typewriting machine, a column- 110 stop bar in the form of a rack, and a stop settable on the bar and comprising a jaw having a plurality of teeth engageable with adjacent teeth on the rack on one side of the latter and a spring jaw engageable with the opposite side of the bar, said spring jaw comprising a sheet-metal finger pivoted to the other jaw and a spring seated in a pocket in the other jaw and bearing upon the sheet-metal finger to close the jaws. 115

7. In a typewriting machine, the combination of a column stop-bar in the form of a toothed rack, a column-stop settable on the bar and including a jaw having a plurality of teeth engageable with adjacent teeth on the toothed side of the bar, and a spring- 120 125 130

- pressed jaw engageable with the opposite side of the bar, the spring jaw including a sheet-metal finger pivoted to the other jaw and arranged to lock the stop to the bar when the stop has been forced into a home position on the bar, and being detented at another point to bear at a single point on the adjacent face of the bar.
8. In a typewriting machine, the combination of a column stop-bar in the form of a toothed rack, a column-stop settable on the bar and including a jaw of hard material, said jaw having a plurality of teeth engageable with adjacent teeth on the toothed side of the bar, said jaw having a tooth depending therefrom and forming an integral part thereof for arresting the carriage, the edges of the teeth on the jaw being tapered and pointed to enable said teeth to readily find their positions between the teeth on the bar, and a spring-pressed detent pivoted to the jaw and arranged to straddle the jaw to provide for a wide face to bear upon the bar at one line only to thereby equalize the pressure upon the bar.
9. In a typewriting machine, the combination of a column stop-bar in the form of a toothed rack, a column-stop detachably settable on the bar and including a solid member formed with a plurality of teeth slidably engageable with adjoining teeth on one side of the bar, and a stop-face at each tooth to limit the sliding engagement thereof, and having a detenting face equal to the width of said member, a spring-pressed detent pivoted to said member, and means to limit the pivotal movement of the detent in two directions.
10. In a type writing machine, the combination of a column stop-bar in the form of a toothed rack, a column-stop settable on the bar and including a jaw having a plurality of integral teeth engageable with adjacent teeth on the rack, an integral elongated stop-tooth depending from the jaw into the path of denominational stops on the machine, and a second, spring-pressed, jaw engageable with the other side of the stop-bar and pivoted to the first jaw.
11. In a typewriting machine, the combination of a column stop-bar having letter-spaced rack-teeth thereon, a detachable column-stop having a plurality of elongated teeth slidably engageable with the rack-teeth to a stop-setting position on the stop-bar determined by a stop-face formed with each tooth of the stop, a detent pivoted on each side of the column-stop including a beveled free end to overhang and engage the stop-bar and a finger-piece to manually release the detent, and a spring housed within the column-stop under the finger-piece to vibrate the detent.
12. In a typewriting machine, the combination of a column stop-bar having letter-spaced rack-teeth thereon, a detachable column-stop having formed integrally therewith a plurality of elongated teeth for a sliding crosswise entrance to the stop-bar and a depending tooth to engage with tabulating mechanism, said tooth being also formed integrally with said column-stop, and a self-opening detent including two ears hung upon pivots at each side of the column-stop to provide for a wide beveled free end to cam over the bar in both directions.
13. A tabulating stop for a combined typewriting and computing machine having a carriage, a slotted rack carried by said carriage for receiving said tabulating stop, and plungers co-operating with the tabulating stop for arresting the carriage, said tabulating stop including a block having teeth milled therein for engaging the slots in the rack, a depending rib for interposing said plungers, said rib forming an integral part of said block, means carried by said block for resiliently holding the block in place, said resilient means including a plate pivotally mounted in the block, said plate having a projection contacting with the side of the rack opposite to the teeth to equalize the pressure of the plate against the rack, and a spring effective between said block and said plate to retain said block.
14. A tabulating stop for a combined typewriting and computing machine having a carriage, a slotted rack carried by said carriage for receiving said tabulating stop, and plungers co-operating with the tabulating stop for arresting the carriage, said tabulating stop including a block having teeth milled therein for engaging the slots in the rack, a depending rib for interposing said plungers, said rib forming an integral part of said block, means carried by said block for resiliently holding the block in place, said resilient means including a plate pivotally mounted in the block, said plate having a projection contacting with the side of the rack opposite to the teeth to equalize the pressure of the plate against the rack, a spring effective between said block and said plate to retain said block, and an inclined surface on said plate for facilitating the insertion of the tabulating stop in place on the rack.
15. A tabulating stop for a combined typewriting and computing machine having a carriage, a slotted rack carried by said carriage for receiving said tabulating stop, and plungers co-operating with the tabulating stop for arresting the carriage, said tabulating stop including a block having teeth milled therein for engaging the slots in the rack, a depending rib for interposing said plungers, said rib forming an integral part of said block, means carried by said block for resiliently holding the block in place, said resilient means including a plate pivot-

ally mounted in the block, said plate having a projection contacting with the side of the rack opposite to the teeth to equalize the pressure of the plate against the rack, a spring effective between said block and said plate to retain said block, and an inclined surface on said plate for facilitating the in-

sertion of the tabulating stop in place on the rack, said inclined surface including a beveled depression at the end of the plate, 10 said depression co-operating with tapered ends of the teeth on the rack.

OTTO THIEME.
